CLAIM

The ornamental design for a lobby dust pan, as shown and described.

DESCRIPTION

FIG. 1 is a top plan view of a lobby dust pan incorporating the features of the invention;

FIG. 2 is a front view thereof;

FIG. 3 is a right side elevational view thereof; the left side elevational view being a mirror image;

FIG. 4 is a rear elevational view thereof; and,

FIG. 5 is a bottom plan view thereof.
